Meyers, Cushman & Co.

UNITED STATES PATENT OFFICE.

HENRY J. PINNEY, OF WORCESTER, MASSACHUSETTS, ASSIGNOR TO THE AMERICAN TOBACCO COMPANY, OF NEW YORK, N. Y., A CORPORATION OF NEW JERSEY.

CIGARETTE-PACKAGE.

1,275,738.

Specification of Letters Patent. Patented Aug. 13, 1918.

Application filed October 29, 1917. Serial No. 198,974.

To all whom it may concern:

Be it known that I, HENRY J. PINNEY, a citizen of the United States, residing at Worcester, in the county of Worcester and 5 State of Massachusetts, have invented new and useful Improvements in Cigarette-Packages, of which the following is a specification.

The present invention relates to a novel 10 cigarette package as well as to the method of dispensing or extracting the cigarettes of the package.

In the present instance I have shown my 15 invention as applicable to cigarette packages of the flexible, pouch or cup type. As is well known, such pouch packages usually comprise a composite sheet of tinfoil and paper folded or wrapped about the cigarettes in such manner as to completely envelop the latter, these wrapped cigarettes being then inserted in a paper pouch or cup having a permanently open mouth at which the top wall or end of the folded wrapper is exposed. The mouth or top of such a 20 pouch package is usually sealed by means of the ordinary revenue stamp which is pasted across such mouth or top to maintain the adjacent folded portions of the wrapper in closed position.

30 One disadvantage incident to the ordinary form of pouch package is that it is so constructed as to necessitate the opening or unfolding of practically the entire top portion of the wrapper, after breaking the revenue stamp, to allow access to and withdrawal of cigarettes. Even after such access has been had an individual cigarette can only be removed by pinching or grasping the exposed end thereof and pulling or 35 withdrawing the cigarette from the package. Of course the cigarettes, especially in a comparatively full package, are tightly packed, and under such conditions, in pinching or grasping the ends of a particular 40 cigarette, the ends of the fingers and especially the fingernails are liable to contact with and break the contiguous ends of adjacent cigarettes.

Another disadvantage inherent in the ordinary type of package of this class is that when it has once been opened by rupturing the revenue stamp and loosening or opening the folds or tucked-in portions of the wrapper sheet at the mouth of the package, 45 such folds cannot be readily restored to and

maintained in their original closed position, even though they be carefully pressed back to again overlie the adjacent ends of the cigarettes as these folds will always have a tendency to again fly open, thus exposing 60 the cigarettes and in many instances allowing the latter to fall or escape from the pouch, especially when the latter is kept in a person's pocket. Furthermore, such an open package will expose the cigarettes to 65 deterioration due to atmospheric influences, in addition to causing the package, under constant handling to break down and lose all semblance of its original form.

With my invention, however, these various 70 disadvantages incident to the ordinary pouch package are avoided, as I provide a package which remains permanently closed and sealed with the exception of a small opening intended to be made by the consumer 75 for the removal or escape of the individual cigarettes, as hereinafter described.

Furthermore, my cigarette package is so constructed that, being maintained permanently and completely sealed with the exception 80 of the above mentioned relatively small opening, it will always present a neat, pouch-like shape and at the same time will efficiently protect the cigarettes from deterioration under atmospheric influences and 85 will prevent such cigarettes becoming disarranged and from escaping or spilling from the pouch.

Another feature of advantage of my 90 package is that while the small opening for the escape of the contents may be instantly and conveniently made by the consumer yet in the manufacture of the package itself and in the quantity, form and character of the material employed no radical departure 95 in manufacturing operation nor increased expense need be incurred in comparison with the production.

When the escape opening has been formed in the package the latter may be manipulated and operated according to a novel method devised by me so as to project the cigarettes through such opening, one or two at a time and into such position that the top ends of the projected cigarettes may 100 be easily and conveniently grasped to completely lift or remove the latter from the pouch without the fingers contacting with or touching those cigarettes remaining in the package. This is an important advantage 105 110

- inasmuch as I obviate entirely the liability of breaking or tearing the adjacent ends of contiguous cigarettes which remain in the pouch and avoid the annoyance and delay 5 commonly encountered in removing the cigarettes.
- I have also found from actual experience extending over a considerable period of time that my unique method of removing the 10 cigarettes from the pouch is a valuable factor from an advertising standpoint, for the facility and rapidity with which the cigarettes may be ejected from the pouch, and the maintenance of sanitary conditions by the 15 avoidance of contact of the fingers with those cigarettes remaining in the package, as well as the novelty and attractiveness of the manner in which cigarettes may be caused to be partially projected from the 20 package, by a simple snap of the wrist or hand, into position to be grasped, all tend to interest and attract purchasers and consumers so that after demonstration of the method by one skilled in the practice thereof 25 these purchasers and consumers will invariably employ such method and will purchase those packages which are so formed or constructed as to enable it to be carried into effect.
- 30 With the above recited objects and others of a similar nature in view, my invention consists in the improved cigarette package and in the method set forth in and falling within the scope of the appended claims.
- 35 In the accompanying drawings:
- Figure 1 is a plan view of the wrapper sheet or blank of my improved package and showing the location of the weakened section thereof.
- 40 Fig. 2 is a perspective view illustrating the package after the application and folding of the wrapper sheet.
- Fig. 3 is a perspective view of the complete package and showing the formation of 45 the escape opening therein by the removal of the weakened section of the folded wrapper sheet.
- Fig. 4 is a perspective view illustrative of the manner in which the package may be 50 held preparatory to projecting the cigarettes therefrom by my improved method.
- Fig. 5 is a similar view illustrating the position of the package and the cigarettes at the completion of the movement of projecting the cigarettes through the escape 55 opening of the package.
- Referring now to the accompanying drawings in detail, the letter A designates the 60 wrapper sheet which as usual is in the nature of a rectangular composite blank composed of flexible, pliable, readily tearable materials, such as tinfoil and paper. At one longitudinal edge, or that edge which is to be folded to close the mouth of the package, 65 this wrapper is perforated, scored or other-

wise marked to form a small, rectangular, weakened section 1 which may be easily and readily torn away to form the escape opening 2 in the top of the package when the wrapper is used to envelop the cigarettes, as 70 is clearly shown in Fig. 2. In the folding of the wrapper sheet A to close the mouth of the package the end folds 3 and 4 are made by folding the wrapper inward over the top ends of the cigarettes, then the side 75 fold 5 is made by lapping the wrapper inward over the end folds, and finally the other or opposite side fold 6 is lapped or folded inward over the side fold 5 so that the mouth of the package is completely 80 closed. This is the usual manner of folding the wrapper sheet to close pouch packages of this type, that is to say, the wrapper sheet is so folded or interfolded that the two side folds will overlap the two end folds, and 85 one side fold will overlap the other. When my wrapper sheet has been folded in this manner the score or perforated lines forming the weakened section 1 of the wrapper will extend along one end edge of the top 90 of the package, substantially co-extensive with such edge, thence along the two side edges of the top of the package but only for a portion of the length of such side edges, the inner terminals of these parallel 95 side edge scorings or perforated lines being connected by transverse scored or perforated line running entirely across the top of the package, so that the result is that when the wrapper is completely folded a rectangular 100 section of less area than the top of the package, but of substantially the same width as the latter will be marked out in such top by the perforated lines. Therefore, when the consumer desires to have access to the cigarettes, it is only necessary to tear away this 105 weakened rectangular section of the wrapper to form the escape opening 2 in the top of the package adjacent one end thereof, the end edge of the top forming the base line of 110 the opening when the package is tilted as shown in Fig. 5 to remove the cigarettes.

In the manufacture of the package, or the preparation of the same for the market the revenue stamp S may be pasted across the 115 top so as to overlie the inner transverse score or perforated line of the weakened section and so as to hold down or seal the folds of the wrapper thereby maintaining the top completely closed and air-tight. 120 The cigarettes enveloped in the wrapper just described are placed in the usual paper cup C, and one end of the stamp may be pasted to this cup and the opposite end of the stamp to the wrapper, or the stamp may be made to extend across the top of the package with opposite ends of the stamp secured to opposite sides of the cup. Of course when the stamp is pasted to seal the top of the package as shown in the drawing, the act of the 130

consumer in tearing away the weakened section to form the escape opening will cause the stamp to be ruptured and destroyed, thus complying with the law as to the destruction of revenue stamps.

After the escape opening has been formed in the package the cigarettes may be readily and conveniently removed by resorting to my method which will be best understood by reference to Figs. 4 and 5. The package may be grasped between the thumb and forefinger at a point preferably a short distance below the transverse median line of the package and a slight pressure exerted to somewhat bend or bow the adjacent end wall of the package. Then with the escape opening uppermost, one cigarette having been previously removed from the pack to loosen the latter, the person may swing or snap the wrist and hand sharply outward through an arc which will of course tilt the package, this sharp, swift outward movement tending to cause the cigarette, or perhaps two of the cigarettes exposed at the opening to slide or be projected therethrough, and were this swinging movement continued, the tendency would be for the cigarette or cigarettes to fly out of the package. However, before this can occur the operator abruptly checks or stops the movement of the hand and wrist thus bringing the package to a stop and at this instant may slightly increase the pressure exerted by the thumb and finger against the opposite side edges of the package. This will cause the outward movement of the cigarettes or cigarette to instantly cease and they will be held in projected position as shown in Fig. 5, and may be then readily and conveniently grasped and lifted out of the package. Of course the remaining cigarettes in the package will be confined or held against escape by the remaining sealed portion of the package top, these remaining cigarettes as well as the adjacent wall portions of the package forming guides for directing the escaping cigarettes through the escape opening. With a little practice a person may readily project one or two cigarettes, or even more, depending upon the size of the escape opening, through the opening at will, and to the desired degree.

While I have herein shown and described a particular embodiment of my invention, I wish it to be understood that I do not confine myself to all the precise details herein set forth as modification and variation may be made without departing from the spirit of the invention or exceeding the scope of the appended claims.

What I claim is:

1. A wrapped package containing cigarettes, including a flexible, pliable wrapper sheet wrapped to inclose the contents of the package, said sheet having a continuous

unbroken edge provided with creased and overlapping interfolds constituting a closure for one end of the package, certain of the creased and overlapping interfolded portions of the wrapper sheet being weakened on a line extending transversely thereof and of the end of the package to provide a tearing section adapted to be torn away to form an opening of less dimensions than the area of the closed end of the package, but large enough to expose a plurality of cigarettes for the escape thereof, a substantial portion of the wall of the opening being co-extensive with and formed by the adjacent end edge of the package, and means for retaining the remaining creased and overlapping interfolded portions intact after removal of the said tearing section.

2. A wrapped package containing cigarettes including a flexible, pliable wrapper sheet wrapped to inclose the contents of the package, said sheet having a continuous unbroken edge provided with creased and overlapping interfolds to constitute a closure for one end of the package, certain of the said overlapping interfolded portions being weakened on a line extending transversely thereof and of the end of the package to provide a tearing section adapted to be torn away to form an opening of less dimensions than the area of the closed end for the escape of the contents of the package, and a seal overlying the creased and overlapping interfolds as such end of the package to maintain the major portion of such end in closed relation after the opening has been formed.

3. A wrapped package containing cigarettes including an inclosing wrapper composed of a rectangular flexible and pliable sheet having a continuous unbroken edge, said wrapper being folded at said edge to provide two side folds and two end folds constituting a closed end of the package, one of said end folds and portions of said side folds being adapted to be torn away to form an opening of less dimensions than the area of the closed end in which such opening is made, but large enough to expose the ends of a plurality of cigarettes, a substantial portion of the wall of the opening being co-extensive with and formed by the adjacent end of the package, and means for maintaining the remaining folded portions intact after the opening has been formed.

4. A wrapped package containing cigarettes, including a flexible, pliable wrapper sheet wrapped to inclose the contents of the package, said sheet having a continuous unbroken edge provided with an irregular weakened line defining a tearable section of less area than the end of the package, the edge of said sheet having the weakened line being provided with creased and overlapping interfolds to constitute a closure for

one end of the package, the construction and arrangement being such that when the sheet is folded in package form, the weakened line will coincide with a substantial portion of 5 the marginal edge of the package and extend transversely across opposite interfolded portions to permit ready removal of the section bounded by the said weakened line and thus provide an opening of less dimensions than

the area of an end of the package, but sufficiently large to expose the ends of a plurality of the cigarettes therein, and means for maintaining the remaining creased and interfolded portions in closed relation after the said tearing section has been removed. 10

In testimony whereof I have hereunto set my hand. 15

HENRY J. PINNEY.
